UNITED STATES PATENT OFFICE

GUSTAVE T. REICH, OF ANAHEIM, CALIFORNIA

MEANS FOR CLEANING GAS CYLINDERS

Application filed January 7, 1927. Serial No. 159,683.

This invention relates to cleaning apparatus for cylinders which are used to store gases under pressure. Compressed gases sometimes contain small quantities of lubricating oil carried over from the compressor, or sulphuric acid used for drying purposes, or other foreign matter. These impurities are deposited in the gas cylinders, and, if allowed to accumulate, they become objectionable for various reasons. It is necessary, therefore, to periodically clean the cylinders of these deposits and an object of this invention is to provide a simple apparatus for readily cleaning gas cylinders.

Another object is to provide apparatus whereby a plurality of cylinders may be simultaneously cleaned and wherein the manual labor required in handling them is reduced to a minimum.

Another object is to provide a new, simple means of treatment, wherein live steam is forced into the cylinders through the safety blow-off connections.

A further object is to provide a novel form of carrier or rack for detachably receiving a plurality of gas cylinders in position for attachment to steam lines.

These and further objects will be apparent from the following description taken in connection with the accompanying drawings wherein

Fig. 1 is an elevation of the cleaning rack with a plurality of cylinders clamped in position.

Fig. 2 is a top view thereof.

Fig. 3 is an end view and

Fig. 4 is a detail, partly in section, showing the means of clamping the steam line to the cylinder.

Referring to the drawings, numeral 1 indicates the gas cylinders, which are shown as mounted on a frame which is substantially Z shaped. This frame comprises a central vertical member 2, from which extend horizontal shelves 3 and 4, these shelves being placed at opposite ends of the member 2 and extending on opposite sides thereof.

This frame or carrier is rotatably mounted by bearings 5 from two vertical struts 6. Each of the shelves 3 and 4 is adapted to re-

ceive a plurality of gas cylinders thereon, as shown. These cylinders are merely placed upon the projecting lower shelf and then are clamped into place by means of a U shaped clamp 7, which is pivoted upon the upright member 2 of the frame. One of these clamps 7 is pivoted to each end of member 2, to clamp the cylinders to its corresponding shelf. These clamps may swing up to clear the upper ends of the cylinders, and when swung down into clamping position, they are retained by the pivoted clips 8. These clips extend nearly the full length of the cylinders and are pivoted to the outside edges of the shelves 3 and 4, and have spring tongues 8' 65 for engagement with the clamps 7.

Against each end of the vertical member 2 and attached thereto, by pipe clamps 9, are steam pipes 10, having their ends screw-threaded for ready attachment to a source of steam supply. A number of branch outlets 11 are connected to steam pipe 10, there being one branch outlet provided for each cylinder adapted to be cleaned. Each of these branches terminates in an enlarged head 12 75 in which is seated a gasket 13, as seen in Fig. 4.

Cylinders of this type are usually provided with domed tops from which project a gas outlet pipe 15. This pipe has a normal 80 outlet 16 for the gas which is controlled by a valve, and an emergency outlet 17. This emergency outlet is usually closed by a frangible piece of metal held in place by a screw-threaded, open-ended cap. For safety purposes, this emergency outlet 17 is at least 50% larger than the normal outlet 16. It is the purpose of this invention to take advantage of this larger opening to facilitate the steaming and draining of the cylinders.

To this end, each branch steam pipe 11 has secured thereto an open rectangular frame 18 adapted for clamping engagement with the cylinder outlet pipe 15. Due to the fact that the main steam pipes 10 are held to the frame 2, by pipe clamps 9, each pipe 10 may be swung or twisted about its axis, so that the branches 11 may be swung down about the pipe clamps 9 as pivots to align the enlarged heads 12 thereof with the emergency 100

outlets 17 of the cylinders, the frangible disks covering openings 17 having previously been removed. Clamping screws 19 are then turned forward to firmly press gaskets 13 5 against outlets 17 to make a steam tight joint, and the row of cylinders is ready to be steamed.

The operation is as follows:

A row of cylinders to be cleaned is placed 10 upon one of the horizontal shelves, say shelf 3, and their frangible disks are removed. Clamp bar 7 is then drawn down and caught in place by clips 8 and spring tongues 8'. Next, the steam pipe 10 is turned and the individual branches 11 lined up with openings 17 in the cylinders, and the clamping screws 19 tightened. The steam pipe 10 is then connected to a source of steam and live steam is forced into the cylinders for the required 15 period of time, depending upon the amount and character of impurities to be removed. After proper steaming, the source of steam is disconnected from pipe 10, clamping screws 19 released and the entire carrier, 20 with its row of cylinders, is rotated 180° about the bearings 5. The cylinders on shelf 3 are now in inverted position, and the condensed steam and foreign matter drains out through openings 17. Another row of cylinders is 25 clamped in place on shelf 4 for steaming. This operation may be continued. It will be seen that the operation of cleaning is simple and may be easily performed by one man. Almost any number of cylinders may be received on such a rack as is shown. By using 30 the safety opening for steaming, wear and tear on the outlet valve is avoided and the cost of labor is greatly reduced.

It will be understood that various changes 40 in structure and design may be made without departing from my invention as expressed in the following claims.

I claim:

1. An apparatus for washing and cleaning 45 gas cylinders of the type having at one end thereof a normal gas outlet and an emergency outlet, said apparatus comprising a carrier, a pipe mounted thereon, means for detachably securing a cylinder to said carrier, and 50 means for detachably connecting said pipe to one outlet of said cylinder, said carrier being pivoted for movement about a horizontal axis, whereby it may be inverted to allow said cylinder to drain.

55 2. In apparatus for cleaning gas cylinders of the type having an outlet at one end thereof, a horizontally-pivoted carrier having a vertical member and a horizontal shelf at each end thereof extending from opposite 60 sides of said vertical member, and means on the carrier for detachably securing a plurality of gas cylinders on said shelves with the outlets of the cylinders on one side of said vertical member facing in opposite direction 65 to the cylinders on the other side thereof.

3. The structure as in claim 2 wherein steam pipes are mounted on the vertical member of said carrier at each end thereof.

4. The structure as in claim 2 wherein the means for securing the cylinders comprises 70 pivoted locking members for contact with the ends of the cylinders and means for holding said locking members against movement.

5. The structure as in claim 2 wherein steam pipes are mounted on the vertical 75 member of said carrier at each end thereof and feeder pipes are provided for detachable connections to the cylinders.

6. A cleaning apparatus for gas cylinders 80 of the type having domed tops with gas outlets in the domed tops, comprising a frame, means thereon for detachably holding a plurality of gas cylinders arranged in two parallel rows, said holding means maintaining one row of cylinders with their domes upright to 85 facilitate cleaning through their gas outlets, and the other row of cylinders in reversed position for draining, said frame being pivoted about a horizontal axis to thereby invert the row of cylinders cleaned by the fluid for 90 draining.

In testimony whereof, I affix my signature.
GUSTAVE T. REICH.
